UNITED STATES PATENT OFFICE

GEORGE HILL, OF WEST WINDSOR, ONTARIO, CANADA, ASSIGNOR TO RALPH L.
SKINNER, OF DETROIT, MICHIGAN

INTERNAL-COMBUSTION ENGINE

Application filed February 9, 1929. Serial No. 338,643.

My invention concerns internal-combustion engines and relates more particularly to means for sealing the pressures in the cylinders in those styles of engines employing reciprocating valves between outer and inner cylinders.

To enable those skilled in this art to fully understand the invention, I have illustrated a present preferred embodiment of the same in the accompanying drawings, forming a part of this specification, and throughout the several views of which like reference characters have been employed to designate the same parts.

In this drawing:

Figure 1 is a substantially-central longitudinal section through one cylinder of a multi-cylinder engine on approximately the line 1—1 of Figure 3;

Figure 2 is an enlarged horizontal section on line 2—2 of Figure 1;

Figure 3 is an enlarged horizontal section on approximately the broken line 3—3 of Figure 1;

Figure 4 is a fragmentary vertical section showing the details of structure of the pressure-sealing means;

Figure 5 is an edge view of the spring employed in the construction illustrated in Figures 1 to 4 inclusive;

Figure 6 is a view similar to Figure 4 of a modified arrangement of parts; and

Figure 7 is a face view of the divided circular spring used in the engine depicted in Figure 6.

Referring to these drawings, it will be apparent that each cylinder of the engine comprises a water-jacketed or otherwise suitably cooled outer cylinder 11 mounted on the top of the usual crank-case 12, the lower portion or sump of which contains the customary supply of lubricating oil.

A thin, inner cylinder 13 is supported from its lower end only by means of screws 14, 14 in concentric relation to the enclosing, outer cylinder with a shallow, annular space between such cylinders, the cylinders 13 having a flat or plane, top, edge surface 15 at right angles to its axis and lower than the inlet and

exhaust ports 16, 17, respectively, of such exterior cylinder.

Cylinder 11 is fitted with a hollow head 18 appropriately mounted thereon and depending into the upper portion of the cylinder, as depicted in Figure 1, such head accommodating the customary spark-plug 19.

That part of the head inside of the cylinder is of slightly less diameter than the latter, thus providing an annular space between them in register with the similar space between the two cylinders.

Conjointly occupying such circular cavities are a pair of sliding, curved or arcuate, inlet and exhaust valves 21 and 22, respectively, reciprocated by suitable crank-shafts 23 and 24 and connecting-rods 25 and 26 located in the crank-case 12, these shafts being rotated at the proper speed by any approved means, not shown, inlet-valve 21 having an admission-port 27 therethrough, an exhaust-valve 22 having a discharge-port 28 through it.

A split, expansible, ported sealing-ring 29 has a flat surface 31 at right-angles to its axis bearing on the cylinder surface 15 and inlet and exhaust ports 32 and 33, respectively, in substantial register with the corresponding outer cylinder-ports.

It is desirable to have the outer cylinder ports slightly wider lengthwise the cylinder than the complementary dimensions of the ports of the sealing-ring, so that the port opening and closing action of the reciprocating valves takes place with respect to the sealing-ring ports rather than with the cylinder-ports.

Such sealing-ring split joint 34 is of the flat type, the ends of the ring having flat, overlapping tongues so that as the ring is expanded by the gas pressure in the cylinder, such joint becomes more securely sealed and pressure-tight by reason of the inner tongue being forced outwardly against the companion, overlapping, outer tongue.

The cylinder and valve inlet-ports 16 and 27 are with advantage provided centrally with comporting bridges 35 and 36, and the sealing-ring joint 34 is located in register with and covered by such part 36, the ring being prevented from turning about its own axis.

axis by reason of a locating or holding pin 37 mounted in the cylinder-head and extending into a recess in the inner face of the ring.

The top surface 38 of the sealing-ring is also plane or flat and at right-angles to its axis and bearing on such surface is the lower edge of an endless, hold-down or confining ring 39 around the lower, reduced-diameter portion 41 of the cylinder-head 18, the two rings 29 and 39 being concentric as shown with the under face of the latter, which presses on the upper face of the former, at right-angles to its axis, whereby the sealing-ring is capable of expansion between the inner cylinder and such confining or hold-down ring.

Ring 39 is pressed or forced down on to the sealing-ring and holds the latter on its bearing on the upper end of the inner cylinder 13 by means of a split or divided, crimped or wavy spring 42 bearing on a circular shoulder 43 of the cylinder-head and on a ring 44, made in two parts, cooperating with a shoulder or ledge 45 on the hold-down ring 39.

Thus the spring, by the instrumentality of the ring 39, holds the sealing-ring down in compression and gas-explosion tight relation with the upper end of the inner cylinder 13, and a like sealing connection is afforded between the ring 39 and the sealing-ring, but without substantial interference with the expansion of the latter, due to such gaseous pressure in the cylinder, against the associated sliding valves, resulting in securing an effective sealing relation between itself and the valves, and between the latter, which it forces outwardly, and the wall of the outer cylinder, whereby gases under substantial pressure in the cylinder cannot escape except through the ports provided therefor, hence permitting the retention of a high compression and an efficient operation of the engine.

It is of distinct advantage to preclude the gaseous pressures of compression and explosion in the engine cylinder from influencing the action of the spring 42 during its ring pressing work, as otherwise the spring would have to be strong enough to overcome such pressures while performing its otherwise useful function, and its effect on the sealing-ring might or would be sufficiently greater to interfere or hinder its expansion which performs the highly important sealing action.

Accordingly, the part 41 of the cylinder-head is supplied with a plurality of external ring-grooves 46, 46, accommodating a like number of split, elastic, expansion rings 47, 47, similar to the usual piston-rings, which press outwardly against the inner surface of the ring 39, whereby the fluid pressure in the cylinder below its head does not have access to the ring 44 or the companion spring 42.

The engine-piston 48, joined to the engine crank-shaft, not shown, by the usual connecting-rod 49, reciprocates in the inner, stationary cylinder, and it and the valves, set forth above, are lubricated in any approved manner with suitable withdrawal of the excess oil to prevent its entrance into the ports, manifold, or combustion-chamber in the cylinder.

The engine operates practically as follows: When the gaseous mixture compression or the explosion pressure occurs in the cylinder, by the construction described, it acts in a way to cause its own sealing and to preclude its leakage, in that it expands or tends to expand the sealing-ring at the same time more effectually sealing or closing its joint 34.

Such enlargement or outward expansion effort of the ring seals the space between itself and the valves, and, by pressing the valves outwardly, seals the space between them and the outer cylinder.

The action of spring 42 seals the joints between the sealing-ring and the top of the inner cylinder and between the hold-down ring and the sealing-ring with adequate pressure to avoid leakage or escape of gases at these points but without substantial opposition to the needed outward pressure of the sealing-ring.

In addition, the rings 47, 47 form a fluid-tight connection between the cylinder-head and the hold-down ring and obviate any leakage at such point, thus precluding the pressure in the cylinder from reaching the spring 42 whose only function is to hold the sealing-ring in position allowing its expansion, but avoiding its up and down travel with the valves against which it presses.

Instead of using the construction described above, the modified arrangement of parts presented in Figures 6 and 7 may be used.

In place of the elements 42 and 44, a divided, flat spring, or two semi-circular flat springs 51, 51, as illustrated, may be employed, with their inner margins securely seated in a shallow, external groove 52, cut in the outer round surface of the part 41 of the cylinder-head, the outer edge portions of the spring sections bearing on a shoulder 53 of the slightly-modified hold-down ring 54.

In this instance, the spring sectors 51, 51 yieldingly press the ring 54 down on to the sealing-ring, the two constructions being the same in other respects and functioning in equivalent manners.

Those acquainted with this art will readily understand that the invention is not necessarily limited and restricted to the precise and exact details of construction presented and that these may be modified within comparatively wide limits without departure from the heart and essence of the invention as defined by the appended claims and without the loss or sacrifice of any of its sub-

stantial or material benefits or advantages.

I claim:

1. In an internal-combustion engine, the combination of an outer cylinder having inlet and exhaust ports, an inner cylinder inside of and spaced inwardly away from said outer cylinder and supported from below with its upper end below said cylinder ports, a piston reciprocatory in said inner cylinder, a connecting-rod joined to said piston and adapted to be connected to a crank-shaft, a split expansible sealing-ring bearing on the upper end of said inner cylinder and having an overlapping joint at its split, said sealing-ring having inlet and exhaust ports in substantial register with said cylinder-ports, an endless hold-down ring bearing on the upper edge of said sealing ring, a cylinder-head for said outer cylinder, spring means bearing on said cylinder-head and hold-down ring to maintain pressure-tight bearings between said sealing-ring and inner cylinder and between said hold-down ring and sealing-ring, expansion ring means between said cylinder-head and hold-down ring preventing fluid pressures in the cylinder from reaching said spring means, inlet and exhaust valves between and slidably lengthwise of said inner and outer cylinders, and means to reciprocate said valves, the joints between said sealing-ring and inner cylinder and hold-down ring being at substantially right-angles to the axis of said cylinder.

2. In an internal-combustion engine, the combination of an outer cylinder having inlet and exhaust ports, an inner cylinder inside of and spaced inwardly away from said outer cylinder and having a bearing surface below said cylinder ports, a piston reciprocatory in said inner cylinder, a connecting-rod joined to said piston and adapted to be connected to a crank-shaft, a split expansible sealing-ring bearing on said surface of said inner cylinder and having an overlapping joint at its split, said sealing-ring having inlet and exhaust ports in substantial register with said cylinder-ports, an endless hold-down ring bearing on the upper edge of said sealing-ring, a cylinder-head for said outer cylinder, spring means bearing on said cylinder-head and hold-down ring to maintain pressure-tight bearings between said sealing-ring and said surface of said inner cylinder and between said hold-down ring and sealing-ring, expansion-ring means between said cylinder-head and hold-down ring preventing fluid pressures in the cylinder from reaching said spring means, inlet and exhaust valves between and slidably lengthwise of said inner and outer cylinders, and means to reciprocate said valves.

3. In an internal-combustion engine, the combination of an outer cylinder having inlet and exhaust ports, a second cylinder inside of and spaced inwardly away from said

outer cylinder and having a bearing surface, a piston reciprocatory in said inner cylinder, a connecting-rod joined to said piston and adapted for connection to a crank-shaft, an expansible sealing-ring having ports therethrough in substantial register with said cylinder-ports bearing on said surface of said inner cylinder, a cylinder-head for said outer cylinder, means including resilient means to press said sealing-ring on such bearing surface of said inner cylinder to prevent pressure-leakage through such bearing, means to prevent the fluid pressures in said cylinder from reaching said resilient means, inlet and exhaust valves between and slidably lengthwise of said cylinders, and means to reciprocate said valves.

In witness whereof I have hereunto set my hand.

GEORGE HILL.
